(57) **CLAIM**

The ornamental design for a hand guard for a firearm, as
shown and described.

DESCRIPTION

FIG. 1 is a left side elevation view of a hand guard for a
firearm attached to a firearm showing our new design;

FIG. 2 is a left, front, bottom view of the hand guard for a
firearm of FIG. 1;

FIG. 3 is a left, front, top view of the hand guard for a firearm
of FIG. 1;

FIG. 4 is a right side elevation view of the hand guard for a
firearm of FIG. 1;

FIG. 5 is a bottom plan view of the hand guard for a firearm of
FIG. 1;

FIG. 6 is a left side elevation view of the hand guard for a
firearm of FIG. 1;

FIG. 7 is a top plan view of the hand guard for a firearm of
FIG. 1;

FIG. 8 is a front elevation view of the hand guard for a firearm
of FIG. 1; and,

FIG. 9 is a rear elevation view of the hand guard for a firearm
of FIG. 1.

The broken lines showing portions of the design in all figures
are included for the purpose of illustrating environment and
unclaimed features and form no part of the claimed design.

1 Claim, 6 Drawing Sheets
